UNITED STATES PATENT OFFICE.

JOHN PATTEN, OF BALTIMORE, MARYLAND, ASSIGNOR OF ONE-HALF TO SAMUEL M. SHOEMAKER, OF ECCLESTON, MARYLAND.

SULFURIC-ACID CONCENTRATION.

1,340,290.

Specification of Letters Patent. Patented May 18, 1920.

Original application filed October 24, 1917, Serial No. 198,324. Patent No. 1,294,827, dated February 18, 1919. Divided and this application filed December 30, 1918. Serial No. 268,872.

To all whom it may concern:

Be it known that I, JOHN PATTEN, a citizen of the United States, and a resident of Baltimore, in the county of Baltimore and State of Maryland, have invented certain new and useful Improvements in Sulfuric-Acid Concentration; and I do hereby declare the following to be a full, clear, and exact description of the invention, such as 10 will enable others skilled in the art to which it appertains to make and use the same.

This invention relates to improvements in sulfuric acid concentration, this application 15 being a division of application for patent filed by me on the 24th day of October, 1917, and designated by Serial No. 198,324.

My invention has reference to what is known as the "cascade system" and one object 20 of the invention is to so manipulate such a system that while the concentrators are working continuously, the scale or sediment of iron and other sulfates which accumulate in the concentrators (particularly 25 those at and near the discharge end of a series of concentrators) will be periodically removed.

A further object is to provide means whereby the containers or concentrators may 30 be cleaned and incrustation and sediment removed without necessity for removing or dismembering said concentrators.

With these and other objects in view the invention consists in certain features as 35 hereinafter set forth and pointed out in the claims.

The accompanying drawing is a sectional view showing one embodiment of an apparatus, whereby my improvements can be 40 carried into effect.

In the concentration of sulfuric acid; using the cascade system; after the concentrators have been in action for a time, an incrustation of sulfates will form in the 45 concentrators. This is especially true where the acid is made from iron pyrites and the incrustation of iron sulfate will form in the concentrators at and near the discharge end of the series, because when the acid reaches 50 these concentrators, most of the water has been evaporated from the acid and the minerals will no longer be held in solution but will be precipitated and form an incrustation which will act as insulation. These 55 concentrators therefore become overheated

and crack or break and discharge the acid into the fire where it will damage the foundations and form larger volumes of sulfur dioxide (SO_2) and other gases, which constitute a nuisance in the neighborhood 60 of the plant, and also result in the loss of a large part of the acid, as well as an interruption in the operation of the plant. In some instances, a leak caused by the cracking of a concentrator due to excessive 65 heat, will subsequently close when the concentrator cools, and it will therefore be difficult to locate the damaged concentrator. Thus in the cascade system of sulfuric acid concentration heretofore practised, great 70 loss has occurred by reason of the cracking or breaking of the concentrators at and near the discharge end of the system. The aim of my present invention is to avoid the difficulties heretofore experienced and to effectually 75 clean the concentrators of sediment and incrustation without removing said concentrators or even opening them, and without stopping the operation of the plant.

In the apparatus shown in the drawing, 80 1 represents a furnace, for supplying heat under a connected series of communicating concentrators 2,—said series of concentrators being inclined and so disposed with respect to the furnace flues, that the greatest 85 heat will be applied to the end of the series into which the acid is fed, as fully explained in my application for patent hereinbefore identified.

At or near one end of the apparatus, two 90 tanks 3 and 4 are located and may be supplied with acid from pipes at 5 and 6 from suitable sources.

The tank 3 is intended to contain acid of a strength of from 60° to 62° Bé., or comprising about eighty per cent. H_2SO_4 and twenty per cent. H_2O ; said acid to be concentrated to approximately 66° Bé. or to a higher degree. The tank 4 is intended to contain a weak chamber acid, containing 95 approximately from thirty-four to thirty-seven per cent. of water. The tanks 3, 4 may discharge over a deflector 7 to a pan 8 and from the latter, by means of a pipe 9 to the first of the concentrators 2. Valves 100 10—11 control the flow of acid from the tank 3 and valves 12—13 may be provided for controlling the flow of acid from the tank 4. The valves 10, 12, 13 may be operated manually, but the valve 10 may be 105 110

operated automatically in the manner fully shown and described in my application hereinbefore identified.

A pipe 14 communicates with the last 5 concentrator of the series and discharges into a receiving tank 14^a, the latter being provided with a water jacket 15, and the acid overflows through a spout 16 to a funnel 17 pivoted to said spout. The pivoted 10 funnel 17 is thus adapted to be made to discharge into one of funnels 18 or 19 communicating, respectively, with pipes 20, 21 and the latter are intended to conduct the acid to separate storage tanks not shown.

15 A pipe 22 may be provided for the escape of steam and aqueous vapors from the concentrators to a drum 23.

When the valves 12—13 are closed and the valves 10—11 open, acid will flow from 20 the tank 3 to the concentrators and in passing through the latter it will be concentrated to approximately 66° Bé. and this will be discharged from the receiving tank 14^a, from which it will pass through the 25 funnels 17—18 and pipe 20 to the storage tank for highly concentrated acid. As nearly all the water has been evaporated out of the acid by the time the latter reaches the discharge end of the series of concentrators 30 and said acid is no longer capable of holding the minerals (sulfates) in solution, the concentrators at and near the discharge end of the series will become coated with incrustation, as previously explained. Without 35 stopping the operation of the apparatus or removing any part of it, weak chamber acid will be run through the concentrators to dissolve and hence remove such incrustation. This may be accomplished by closing 40 the valves 10—11 and opening one or both of the valves 12—13, thus stopping the feed of acid from the tank 3 and starting the supply of weak chamber acid from the tank 4. When the valves are thus shifted, the 45 operator will move the funnel 17 out of line with the discharge funnel 18 and he will move said funnel 17 to position to discharge acid to the funnel 19, so that the weaker acid may be conducted through the pipe 21 to 50 the separate tank provided for it. When the acid from the tank 4 passes through the concentrators as above described, it will dissolve the incrustation as previously explained and it will also be concentrated to 55 from 60° to 62° Bé., and will therefore contain sufficient water (from 34 to 37 per cent. or as low as 20 per cent.) to dissolve the minerals and hold the same in solution, care being exercised not to run this weak acid 60 through the concentrators at such a slow speed as might cause too great concentration to insure the dissolving and holding in solution of the minerals. The acid resulting from the cleaning process, may be conducted 65 ed, in any suitable way from the storage

tank to the tank 3 and again passed through the concentrators for the manufacture of 66° acid.

When the incrustation shall have been removed as above explained, the operator may 70 close the valves 12—13 and then the apparatus may be operated for the concentration of the stronger acid from 3. As soon as 66° acid begins to flow from the receiving tank 14^a, the operator will shift the funnel 17 so 75 that this 66° acid will be conducted to the pipe 20 and to the storage tank provided to receive it.

By alternately passing strong and weak acid through the concentrators at proper 80 speeds, the incrustation caused by the concentration of the stronger acid to 66° Bé., will effectually be removed by the weak acid, and the operation of the apparatus and the method will be a continuous one. 85

Having fully described my invention, what I claim as new and desire to secure by Letters Patent, is:—

1. The combination with a connected series of concentrators and means for heating the same, of two valved sources for feeding acid to one end of said series of concentrators, two receiving means for acid from the concentrators, and means for shifting the discharge of acid from one of said receiving means to the other. 95

2. In sulfuric acid concentration apparatus, the combination of a connected series of concentrators and means for heating the same, of separate sources of weak and 100 stronger acid for supplying acid to the concentrators, means for controlling the flow of acid from one or the other of such sources, two receiving means for acid from said concentrators, and means for directing acid into one or the other of the receiving means, whereby the apparatus may be operated alternately to concentrate acid to a high degree and operated to condense acid to a lesser degree and dissolve incrustation left 110 by the first-mentioned concentration, and whereby the acid resulting from the two concentrations may be separately recovered.

3. The combination with a connected series of concentrators and means for heating the same, of two valved sources for feeding acid to one end of said series of concentrators, two discharge pipes, a funnel on each of said discharge pipes, a receiver for concentrated acid from the concentrators, 115 and a spout for conveying acid from the receiver to the funnel on one or the other of said discharge pipes. 120

4. The combination with a connected series of concentrators and means for heating the same, of two valved sources for feeding acid to one end of the series of concentrators, a receiver at the other end of the series of concentrators, two receiving pipes for acid from said receiver, and adjustable 125 130

means between said receiver and receiving pipes for causing the acid from the receiver to be directed to one or the other of said receiving pipes.

5. The combination with a connected series of concentrators, and means for heating the same, of two valved sources for feeding acid to one end of said series of concentrators, a receiver for concentrated acid at 10 the other end of the series of concentrators,

two discharge pipes, a funnel on each of said discharge pipes, a spout communicating with the receiver, and a funnel pivotally mounted on said spout and adapted to be made to discharge into the funnel of either 15 of the discharge pipes.

In testimony whereof I have signed this specification.

JOHN PATTEN.
